ARTIFICIAL BODY MEMBERS

Frank V. Eberle, Newark, and Harry Hansen,
Lyndhurst, N. J.

Application April 27, 1946, Serial No. 665,543

16 Claims. (Cl. 3—12)

1

This invention relates to artificial body members, more particularly to artificial hand and wrist assemblies, and has for an object to provide a novel connection between artificial hand and wrist members.

Another object of the invention is to provide an artificial hand and wrist assembly in which the hand may be rotated about the axis of the wrist member and locked in any desired position of such rotation.

A further object of the invention is to provide an artificial hand and wrist assembly wherein the hand may have an infinite number of positions of rotation relative to the axis of the wrist member.

Yet another object of the invention is to provide an artificial hand and wrist assembly wherein the hand and wrist members are retained in the desired position of relative rotation by frictional contact of mating surfaces thereon.

Yet another object of the invention is to provide a hand and wrist assembly in which the hand member may be readily attached to, and separated from, the wrist member.

These and other objects are effected by the invention as will be apparent from the following description and claims taken in accordance with the accompanying drawings, forming a part of this application, in which:

Fig. 1 is an elevational view, partially in section, of an artificial wrist and hand assembly embodying the principles of the present invention;

Fig. 2 is a bottom plan view of the structure shown in Fig. 1;

Fig. 3 is an exploded view of the wrist and hand members of Fig. 1, half in elevation and half in section;

Fig. 4 is a sectional view, taken along the line IV—IV of Fig. 3, looking in the direction indicated by the arrows;

Fig. 5 is a fragmentary view of a portion of the structure shown in Fig. 3; and,

Fig. 6 is a sectional view, taken along the line VI—VI of Fig. 1, looking in the direction indicated by the arrows.

Referring now to the drawings more in detail, the reference character 10 indicates, in its entirety, an artificial hand and wrist assembly comprising a hand member 11 and a wrist member 12, shown locked in assembled relation in Fig. 1 and shown separated in Fig. 3.

The hand member 11 comprises a housing 13, shaped and finished to simulate the human hand.

The wrist end of the hand housing 13 includes

2

an inwardly-directed flange 14 against whose radial surface 16 is secured, by screws 17, a pressure ring 18, for a purpose to be hereinafter described. The inner edge of the flange 14 is beveled to provide a frusto-conical seat 19 for a mating frusto-conical surface 21 on a projection 22 integral with the wrist housing 23.

With the exception of a flange 24 at the hand end of the wrist housing 23, the latter is of reduced diameter to provide space for the wrist end of the usual leather cuff, shown in phantom at 25, the other end of the cuff containing a socket for the natural arm stump in the case of a forearm amputation.

It should be noted that the mating frusto-conical surfaces 19 and 21 are of such dimensions that when they are in tight mating engagement the adjacent surfaces of the flanges 14 and 24 are slightly spaced, with the result that any force tending to urge the wrist and hand housings towards each other is received entirely by the mating frusto-conical surfaces 19 and 21, the resulting increased frictional engagement of these surfaces preventing rotation of either housing relative to the other.

The frusto-conical projection 22 is bisected by a slot 27, milled or otherwise formed therein, and two pairs of ears or lugs 28 extend outwardly from the end of the projection 22, the lugs of each pair being disposed at opposite sides of the slot 27, and the two pairs being positioned at opposite sides of the longitudinal axis of the hand and wrist assembly 10, preferably near the inner periphery of the pressure ring 18 when the wrist and hand members are assembled.

Circumferentially aligned with the terminal portions of the slot 27 and with the pairs of lugs 28 are a pair of bores 29 extending from the rear end of the wrist housing 23 towards the front or hand end thereof and in parallel relation to the assembly longitudinal axis at least a distance sufficient to assure that the bores 29 open into the bottom of the slot 27, whereby the two bores 29, in cooperation with the slot 27, provide a pair of passages open from end to end of the wrist housing.

A pair of bell cranks 30 and 31 are pivotally mounted, at 32, to the pairs of lugs 28. The bell crank 30 comprises a long arm 33, extending through and beyond one of the bores 29 and the aligned portion of the slot 27, and a short arm 34 extending substantially at right angles to the long arm 33 with its terminal portion engaging the free surface of the pressure ring 18. Similarly, the second bell crank 31 comprises a long

arm 36 disposed in the other bore 29 and a short arm 37 likewise engaging the free surface of the pressure ring 18 at a point diametrically opposed to the point of engagement of the arm 34 of the first bell crank 30.

A relatively short lever 38 is pivotally connected, as at 39, to the free end of the long arm 33 of the first bell crank 30. One end of this lever 38 is pivotally connected, by pin 40, between a pair of ears 41 at one end of a yokelike link 42 at whose other end a similar pair of ears 43 are connected by pin 44 to the free end of the long arm 36 of the second bell crank 31. A latch member 46 is pivoted at one end, at 47, to the other end of the short lever 38 and has its free end 48 projecting through an opening 49 in an extension 51 carried by the wrist housing 23. Preferably, the free end 48 of the latch 46 is shaped as a knob to facilitate manipulation of the latch either manually or by engagement with any relatively stationary object.

It will be apparent that the link and lever arrangement just described provides for movement of the latch inwardly and outwardly in directions transverse to the longitudinal axis of the hand and wrist assembly. In Fig. 1, the latch 46 is shown in its innermost position where it is held by engagement of a locking tooth 52, formed integral with the latch, against the inner surface of the wrist extension 51. Downward movement of the knob 48 will disengage the locking tooth 52 from the extension 51, permitting outward movement of the latch 46.

The linkage is so arranged that when the parts thereof are in the positions shown in Fig. 1, the short arms 34 and 37, respectively, of the bell cranks 30 and 31, press against the pressure ring 18 of the hand member 11 and urge the frusto-conical surfaces 19 and 21 into sufficiently firm engagement to insure that the hand member 11 cannot be rotated relative to the wrist member 12.

When the latch 46 is moved downward and the locking tooth 52 thereof disengaged from the inner surface of the wrist extension 51, the latch is free to move outwardly and such movement will occur to at least a degree sufficient to relieve any stresses present in the linkage when in wrist-locking position.

With the latch in unlocked position, no forces are transmitted through the linkage to the pressure plate 18, and the friction between the mating frusto-conical surfaces 19 and 21 will be so small as not to interfere with rotation of the hand member 11 relative to the wrist member 12.

Heretofore, hands of this character have been pretty much limited in respect to positions of adjustment of the hand member about the longitudinal axis of the hand and wrist assembly, due to the locking being accomplished by insertion of a pin into one of a series of holes or notches, and the number of positions of adjustment obtainable being limited to the number of holes or notches provided. With a hand and wrist assembly constructed in accordance with the present invention an infinite number of positions of adjustment may be obtained.

In operating the mechanism herein described, and assuming the latch 46 in unlocked position, the hand member 11 is rotated to the desired position relative to the wrist member 12 and the latch pushed inwardly and upwardly until the locking tooth 52 engages the inner surface of the wrist extension 51. As the latch moves inwardly it acts on the short lever 38, at 47, to swing the

lever counterclockwise about its central pivot 39, as viewed in Figs. 1, 3 and 5. The lower end of lever 38 will operate through pin 40 and ears 41 to move link 42 to the right, thereby moving 5 radially inward the long arm 36 of bell crank 31. When inward movement of arm 36 has been limited by tight engagement of short arm 37 against pressure ring 18, further inward movement of latch 46 will pivot lever 38 about pin 40, thereby 10 producing radial inward movement of long arm 33 of bell crank 30. When latch 46 is in locked position, the two short bell crank arms 34 and 37 will both press firmly upon the pressure ring 18, locking the hand and wrist members against 15 rotation. Although as described above it appears that one bell crank moves before the other, actually they both move simultaneously, the force applied through the latch 46 being at all times equally divided between the two bell cranks. 20 Furthermore, there actually is very little movement of the bell cranks, most of the movement of the latch merely applying stresses to, or removing stresses from, the bell cranks.

To insure that the bell cranks assume a non-stressed position relative to the pressure ring when the latch is unlocked, a bowed spring 54 is positioned with its terminal portions engaging in notches 56 in the inner edges of the long arms of the bell cranks, the spring 54 at all times exerting forces on the bell cranks tending to move their long arms radially outward.

Where the hand member 11 includes movable digits, it is desirable to provide an operating rod extending axially of the hand and wrist assembly 35 and adapted to actuate the digits upon application of pressure or motion to the wrist end thereof. In order that the wrist joint of the present invention may be readily turnable, and also axially separable, the operating rod comprises a first 40 wrist section 57 and a second hand section 58 having a separable swivel connection at their adjacent ends. The operating rod wrist section 57 terminates in a spherical member 59 forming the male portion of a ball and socket joint whose 45 female member comprises a cylindrical cross-head 61 slidable and rotatable in a cylindrical central bore 62 extending from end to end of the wrist housing 23.

The crosshead 61 is provided at its forward end 50 with a cylindrical projection 63 terminating in an annular flange 64 having a keyway 66 in its periphery (Figs. 1 and 6).

The adjacent end of the operating rod hand 55 section 58 has a socket member 68 threadedly mounted on the operating rod, at 69, and secured there by the lock nut 71. The socket member 68 has a cylindrical bore 72 closely receiving the flange 64 of the crosshead 61, the bore being provided at one side with a radial inwardly-directed key 73 slidably fitting the keyway 66. The key 73 is broken midway of its length, the gap 74 at the break being of sufficient width to receive the mating flange 64 of the crosshead, with the result that when the flange is assembled in the socket member bore 72 with the key and keyway engaging, and the parts are then rotated relative to each other, the flange 64 will be received in the gap 74 and locked against axial movement relative to the socket member. It will be noted that the end of the crosshead cylindrical portion 63 and its flange 64 do not engage the bottom of the socket member bore 72 but rest on the inner portion of the broken key 73, thereby permitting tilting of the operating rod 75

hand, section 53 to the limited extent necessary in its operation of the hand's digits.

When the mating cylindrical projection 63 and the socket 68 are in the relative positions shown in Figs. 1 and 6, they are locked against relative longitudinal movement and can be separated only upon rotation of one relative to the other through 180 degrees, whereupon the key 73 and keyway 66 will be in alignment.

Similarly, the hand housing 13 and wrist housing 23 can be separated only when the short arm 34 of bell crank 33 overlies the slot 77 in the pressure ring 18, at which time the projection 63 and socket 68 of the operating rod mechanism are also aligned, permitting complete separation of the hand from the wrist. When in use, the hand housing 13 is turned 180 degrees from the position of separation, as shown in Fig. 6. In this position, the lateral projections 78 of the short arm 37 of bell crank 36 prevent this short arm from passing through the slot 77 of the pressure ring 18. In separating the hand from the wrist, after turning the parts 180 degrees from the position shown, the short arm 34 of bell crank 33 can be moved through the slot 77 by a tilting action, whereupon the other short arm 37 will slip off the pressure ring 18.

While the invention has been shown in but one form, it will be apparent to those skilled in the art that it is not so limited, but is susceptible of various changes, modifications and applications without departing from the spirit thereof.

What is claimed is:

1. In an artificial body structure, a wrist member, a hand member, a frusto-conical projection on one of said members, the other of said members having a mating frusto-conical opening adapted to closely receive said projection, and means carried by one of said members and movable between a first position where it urges the mating frusto-conical surfaces into mating relation with sufficient frictional engagement to prevent relative rotation of said surfaces and a second position where it releases said surfaces from mating relation sufficiently to permit relative rotation thereof.

2. Structure as specified in claim 1, including a latch which when in latched position retains the last-mentioned means in its first position and when in unlatched position permits movement of said last-mentioned means to its second position.

3. In an artificial body member, a wrist member, a frusto-conical projection on said wrist member, a hand member having a frusto-conical opening in the base thereof adapted to closely receive the frusto-conical projection of the wrist member with the frusto-conical surfaces mating, and means carried by the wrist member and movable between a first position where it retains said surfaces in mating relation and a second position where it releases said surfaces from mating relation.

4. Structure as specified in claim 3, including a latch which when in latched position retains the last-mentioned means in its first position and when in unlatched position permits movement of said last-mentioned means to its second position.

5. In an artificial body structure, a wrist member, a hand member, means releasably securing said hand member to said wrist member and adapted to lock them in any desired position of rotation of the former relative to the latter, said securing means comprising structure providing

mating surfaces on said members, a bell crank pivotally mounted on one of said members, and means for applying a force to one arm of said bell crank to cause the other arm thereof to exert pressure on the other of said members to force said mating surfaces into locking frictional engagement.

6. Structure as specified in claim 5, including means for releasably locking the last-mentioned means in force-applying position.

7. In an artificial body structure, a wrist member, a hand member, means releasably securing said hand member to said wrist member and adapted to lock them in any desired position of rotation of the former relative to the latter, said securing means comprising structure providing mating surfaces one on each of said members, a plurality of bell cranks pivotally mounted on one of said members, means for applying a force to one arm of one of said bell cranks to cause the other arm thereof to exert pressure on the other of said members to force said mating surfaces into locking frictional engagement, and means for distributing any force applied to said one bell crank among the plurality of bell cranks.

8. Structure as specified in claim 7, wherein said last-mentioned means distributes uniformly among the plurality of bell cranks any force applied to said one bell crank.

9. Structure as specified in claim 7, including means for releasably locking in force-applying position the means for applying a force to said one bell crank.

10. Structure as specified in claim 7, including resilient means exerting pressure on the first-mentioned arms of said bell cranks in a direction opposed to any force applied by said force-applying means.

11. Structure as specified in claim 5, including resilient means exerting pressure on the first-mentioned arm of said bell crank in a direction opposed to the force exerted thereon by said force-applying means.

12. In an artificial body structure, a wrist member, a hand member, a frusto-conical projection on one of said members, the other of said members having a mating frusto-conical-walled opening adapted to closely receive said projection, a plurality of bell cranks pivotally mounted on one of said members, and means for applying a force to one arm of each of said bell cranks to cause the other arm of each bell crank to exert pressure on the other of said members to force said mating surfaces into locking frictional engagement.

13. In an artificial body structure, a wrist member, a hand member, a frusto-conical projection on one of said members, the other of said members having a mating frusto-conical-walled opening adapted to closely receive said projection, a plurality of bell cranks pivotally mounted on one of said members, means for applying a force to one arm of one of said bell cranks to cause the other arm thereof to exert pressure on the other of said members to force said mating frusto-conical surfaces into locking frictional engagement, and means for distributing any force applied to said one bell crank by said force-applying means to the plurality of bell cranks for corresponding action of the latter in parallel on said other member.

14. In an artificial body structure, a wrist member, a hand member, means releasably securing said hand member to said wrist member and adapted to lock them in any desired position of rotation of the former relative to the latter, said

securing means comprising structure providing mating surfaces one on each of said members, a pair of bell cranks pivotally mounted on one of said members in opposed relation at opposite sides of the longitudinal axis of said member, a lever pivoted intermediate its terminal portions to the terminal portion of one arm of one of said bell cranks, a link pivotally joined at one end to a terminal portion of said lever and at the other end to the terminal portion of an arm of the other of said pair of bell cranks, a latch pivotally connected at one end to the other terminal portion of said lever, movement of said latch into one position operating through said lever and link to move said arms of said pair of bell cranks in opposite directions and to cause the other arm of each of said bell cranks to exert pressure on the other of said members to force said mating surfaces into locking frictional engagement.

15. Structure as specified in claim 14, including means for locking said latch in said one position.

16. In an artificial body structure, a wrist member, a hand member, means providing a pair of mating surfaces one on each of said members, a first operating rod mounted in said wrist member for sliding movement axially thereof, a second operating rod mounted in said hand mem-

ber and adapted to be reciprocated by said first operating rod, means separably connecting said rods, a pair of bell cranks pivotally mounted on said wrist member in opposed relation at opposite sides of the longitudinal axis of said operating rods, means for applying a force to one arm of one of said bell cranks to cause the other arm thereof to exert pressure on the hand member to force said mating surfaces into locking frictional engagement, and a yoke-like link having clearance with respect to said operating rods and connecting said bell cranks for distributing equally between the latter any force applied to said one bell crank by said force-applying means.
